UNITED STATES PATENT OFFICE.

WILLIAM R. HOTCHKISS, OF ST. PAUL, MINNESOTA.

CHECK BOOK.

Application filed May 7, 1928. Serial No. 275,849.

My invention relates to a blank book particularly, although not exclusively, adapted to contain a supply of blank checks or the like together with stubs for the entry of memoranda relative to the issued checks.

It is my object to provide a book of this kind, the superficial area or size of which is reduced to a minimum by a novel arrangement of stub and check blanks.

Other objects of this invention are to facilitate drawing checks and entry of memoranda on the stubs by eliminating the usual obstructions in books of this kind while locating the exposed stubs directly opposite the corresponding blank checks and otherwise adapting the device to the convenience and established custom of the users. The invention also includes certain other novel features of construction which will appear and be more fully pointed out in the following specification and claims.

In the drawings Figure 1 is a plan view of my improved check book in open position; Fig. 2 is a fragmentary section of the same showing the front or top cover in closed position and taken on the line 2-2 of Fig. 1; Fig. 3 is a similar sectional view but taken on the line 3-3 of Fig. 1; Fig. 4 is a section taken on the line 4-4 of Fig. 3; Fig. 5 is a perspective view of the book in open position and with only one set of the blanks in place on the binding members; Fig. 6 is a bottom plan view of the metal support and locking means for the binding members; Fig. 7 is a detail plan view of the support and binding members removed from the covers and Fig. 8 is an enlarged section taken on the line 8-8 of Fig. 7.

My improved book is preferably provided with a rigid back cover 9 connected by a hinge member 10 with a front or top cover 11. Along one margin of the back cover 9 is secured a metal support 12 having a pair of binding posts 13 and U-shaped binding members 14 projecting therefrom. The posts 13 are rigidly secured to the support 12 and have tapped holes in their upper ends to receive binding screws 15. The U-shaped binding members 14 are preferably made removable and provided with a locking means like that described in my copending application, Serial #207,423, filed July 21st, 1927. Thus hollow impaling members 16 are rigidly secured to the support 12 and each arranged to receive one end of a U-shaped member 14. The other end of the member

14 has a kerf 17 to receive a slidable locking bar 18, the kerfed end being insertable into an opening in the support 12, as best shown in Fig. 8. The bar 18 is slidable upon the bottom surface of the support 12 and has an upturned flange 19 on one end which is accessible for operating the lock. Suitable guide tongues 20 and 21 are struck downward from the support 12 to engage the lateral edges of the bar 18, the tongue 21 being arranged to limit movement of the bar 18 by engagement with a slot 22 in an edge of the same. Notches 23 are cut in an edge of the bar 18 to register with the kerfs 17 in the members 14 so that said members may be released and withdrawn from the support 12 and impaling members 16.

Sheets 24 of blank stubs are interleaved between sheets 25 of blank checks in the formation of a rectangular body or pad for insertion between the covers 9 and 11. Each of the sheets 25 has a marginal projection 26 which is perforated to receive the binding posts 13. The sheets 24 of stubs are cut away at their margins where they would otherwise register with the projections 26. Thus each of the sheets 24 has a pair of marginal projections 27. These projections 27 are formed with perforations 28 adapted to receive the U-shaped binding members 14 and impaling members 16.

It will now be understood that separate binding members are provided for the blank checks and stubs respectively, so that when the front cover is extended in open position all of the sheets 24 of stubs may be removed from the top or superficial sheet 25 of blank checks and laid flat at the opposite side of the binding members. Both the top sheet of checks and corresponding stubs are thus exposed in the most convenient arrangement for writing thereon.

As illustrated, each of the sheets 25 is divided into three check blanks by perforating along parallel lines 29 and two of the sheets 25 are placed between adjacent sheets 24 in the formation of the body of blanks. To facilitate tearing out the checks as they are drawn, the sheets 25 are also perforated along a line 30 forming the junction between the check blanks and the marginal projections 26. To further facilitate tearing along the line 30, I prefer to place a bar 31 upon the top projection 26, this bar being perforated to receive the binding screws 15. The several projections 26 are gripped or bound

together, independently of the projections 27 on the sheets 24, by turning down the screws 15 into the posts 13.

Each of the sheets 24 may be divided by lines 32, 33 and 34, or otherwise printed upon, to afford the same number of blank stubs on a sheet 24 as there are blank checks upon the corresponding sheets 25. As shown, six stubs are indicated on a sheet 24, in two vertical columns of three each. The three stubs in a column are directly opposite the three corresponding checks on a sheet 25. Two of the sheets 25 are provided for each sheet 24 so that the proper stub blank is always exposed opposite the superficial or top check blank. Because of my arrangement of the stub blanks horizontally opposite the corresponding checks, the device meets the requirements of users most of whom are in the habit of entering the stub memoranda opposite a check when it is drawn.

As will now be readily understood, when it is desired to insert a body of blanks, with 25 stubs interleaved between the checks, the U-shaped binding members 14 may be removed from the support 12 by sliding the locking bar 18 to a position where the notches 23 register with the kerfs 17. This frees the members 14 so that they may be withdrawn from the impaling members 16. The screws 15 are removed together with the bar 31 so that the posts 13 and impaling member 16 are free to receive the body of blanks 30 having perforated marginal projections 26 and 27. Now the blanks may be quickly and easily positioned with the binding members 35 in engagement with the marginal projections and the bar 31 and screws 15 may then be replaced to bind the check blanks together. To bind the sheets 24 of stub blanks together, it is only necessary to insert one end of each 40 of the members 14 into a hollow impaling member 16 and the other end through the opening in the support 12 adjacent to the locking bar 18. Finally the edge of the 45 bar 18 is returned to interlocking relation with the members 14 by sliding it longitudinally into the kerfs 17.

The body of blanks thus inserted and secured in place is composed of sheets of blank stubs equal in size to the sheets of check blanks. This feature of the invention promotes 50 convenient handling of the blanks before and after binding and makes it possible to utilize the same, or a like, cover to bind the stub memoranda for subsequent reference and filing.

Binding means other than those illustrated may be employed within the spirit of my invention and I do not wish to limit the invention to its use with any particular means for separately binding the interleaved check and stub blanks.

Having described my invention what I

claim is new and desire to protect by Letters Patent is:

1. A check book comprising interleaved stub and check blanks, marginal projections on the check blanks superimposed one upon another in a series, means for binding said projections together, separate marginal projections on said stub blanks and loose leaf binding means engaging said projections on the stub blanks adapted to permit separation of the latter one at a time from the unused check blanks. 70

2. A check book comprising interleaved stub and check blanks, marginal projections on the check blanks, means for binding said projections together, separate marginal projections on said stub blanks and arcuate binding members engaging said projections on the stub blanks adapted to permit separation of the latter one at a time from the 85 unused check blanks.

3. A check book comprising interleaved sheets of check and stub blanks, a cover, impaling member near a margin of said cover, marginal projections on said check blank, 90 means for binding said projections together above said margin of said support, arcuate sheet retaining members connected to said impaling members and separate marginal projections on said stub blanks perforated to receive said arcuate and impaling members, said stub blanks being arranged to be separated from the unused check blanks and transferred to the opposite side of said impaling members while in engagement with 100 said arcuate members.

4. A check book comprising interleaved sheets of check and stub blanks of substantially equal size, a cover, a binder support extending along a margin of said cover, 105 marginal projections on said check blanks, means for binding said projections together upon said support, a pair of arcuate binding members secured to said support and separate marginal projections on said stub blanks perforated to receive said arcuate binding members, said stub blanks being arranged to be separated from the unused check blanks and transferred to the opposite side of said support while in engagement with 115 said arcuate binding members.

5. In a check book, front and back covers foldably secured together and arranged to lie flat when in open position, sheet-impaling members near a margin of said back cover, a body of interleaved check and stub blanks adapted to be secured to said back cover, marginal projections on said check blanks, separate marginal projections on said stub blanks, sheet retaining members connected to said impaling members and engaging said last-mentioned projections and means for binding said projections on the check blanks together independently of said impaling members, said stub blanks being arranged to 130

be separated from the unused check blanks and transferred to the opposite side of said impaling members while in engagement with said sheet retaining members whereby the 5 check blanks and corresponding stub blanks may be laid flat and simultaneously exposed upon the back and front covers for writing thereon.

6. In a check book, front and back covers 10 foldably secured together and arranged to lie flat when in open position, two pairs of impaling members disposed along a margin of said back cover, a body of interleaved check and stub blanks, marginal projections 15 on said check blanks perforated to receive one pair of said impaling members, separate marginal projections on said stub blanks perforated to receive the other pair of im-

paling members, a pair of arcuate members connected to the impaling members and engaging said last-mentioned projections and means for binding said projections on the check blanks together independently of the stub blanks, said stub blanks being arranged to be separated from the unused check 25 blanks and transferred to the opposite side of said impaling members while in engagement with said arcuate members whereby the check blanks and corresponding stub blanks may be laid flat upon the back and 30 front covers in exposed positions for writing thereon.

In testimony whereof, I have hereunto signed my name to this specification.

WILLIAM R. HOTCHKISS.
